UNITED STATES PATENT OFFICE.

ROBERT NORDENSWAN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE RECEIVER.

Application filed October 31, 1923. Serial No. 671,869.

This invention relates to telephone receivers and its object is to provide a telephone receiver, the operation of which is unaffected by temperature changes.

5 In general, the invention provides a telephone receiver in which the clamping means has substantially the same coefficient of expansion as that of the diaphragm and means are provided to insure a positive and uniform clamping pressure at all points.

In its preferred embodiment, the invention provides a receiver with a diaphragm mounting consisting of an iron clamping member and an iron seat in threaded en-

15 gagement therewith between which the diaphragm is clamped, pressure being exerted on the diaphragm through an iron ring having a plane clamping surface disposed against the diaphragm and a soft copper

20 gasket between said ring and clamping member.

The drawing shows a cross section of a receiver embodying the invention. The electromagnetic unit 2, preferably of the type disclosed in Patent 1,273,351, July 23, 1919, H. A. Frederick, is mounted in a cup 3 preferably of non-magnetic material. Thread-

25 30 engaging the cup 3 is an annular seat 4 of iron or any material having the same coefficient of expansion as that of diaphragm 5 seated thereon in operative relation to the electromagnetic unit 2. The cap of the receiver consists preferably of a clamping ring 6 of iron or some material having the

35 same coefficient of expansion as that of the diaphragm 5 and an earpiece 7 preferably of insulating material, such as hard rubber, threadedly engaging the clamping member 6. Between the clamping member 6 and the

40 diaphragm 5 is disposed a metal ring 8 such as iron or some material having the same coefficient of expansion as the diaphragm. The narrow plane surface of ring 8 is disposed against the diaphragm and a yielding gasket 9 of copper, or other soft material,

45 through which the pressure of the clamping ring 6 is transmitted to the ring 8 is disposed between the member 8 and ring 6. The clamping ring 8 being of hard ma-

50 terial insures a positive and unvarying clamping surface, and the gasket 9 being of soft material insures the pressure exerted by clamping ring 6 being evenly distributed around the diaphragm. The inner surface

of the angular member 4 is provided with 55 an annular recess 10 in which is fitted a plate 11 having a central opening through which the receiver pole pieces extend. Between the plate 11 and the diaphragm 5 is disposed a plurality of annular disks 12 of 60 aluminum foil or paper for damping the vibrations of the diaphragm 5, the total thickness of the disks 12 when compressed being slightly less than the distance between the plate 11 and the diaphragm 5. 65

While the invention has been illustrated in connection with a telephone receiver, it may be employed in telephone transmitters and phonograph reproducers and recorders. It is especially suitable for instruments 70 which are to be used in connection with scientific investigations and as standards of comparison.

What is claimed is:

1. In a receiver, a diaphragm, a seat therefor, a clamping member engaging said seat, a ring disposed against said diaphragm and a yielding metal gasket between said ring and said clamping means, whereby the clamping pressure is distributed uniformly 80 on said diaphragm. 75

2. In a telephone receiver, a diaphragm, a seat therefor having a plane surface, a ring having a plane surface disposed against said diaphragm, a yielding metal gasket disposed 85 against said ring, a clamping member engaging said seat to secure said diaphragm, said clamping member, said seat, said ring, and said diaphragm having the same coefficient of expansion. 90

3. In a telephone receiver, a seat, an annular ring, a diaphragm between said ring and said seat, a metal clamping member, said diaphragm, said seat and said ring having the same coefficient of expansion, and a 95 yielding metal gasket between said clamping member and said ring whereby uniform pressure may be exerted upon said diaphragm.

4. In a telephone receiver, a diaphragm, 100 a seat, an annular member and clamping means for clamping said diaphragm between said seat and said annular member, all of said parts being constructed of materials having the same coefficient of expansion. 105

In witness whereof, I hereunto subscribe my name this 26 day of October A. D. 1923.

ROBERT NORDENSWAN.
